(57) **CLAIM**

I claim the ornamental design for a cosmetic device, as shown and described.

DESCRIPTION

FIG. 1 is a top, right, front perspective view of an embodiment of the claimed design;

FIG. 2 is a top, right, rear perspective view of the claimed design of FIG. 1;

FIG. 3 is a front elevation view of the claimed design of FIG. 1;

FIG. 4 is a rear elevation view of the claimed design of FIG. 1;

FIG. 5 is a right elevation view of the claimed design of FIG. 1;

FIG. 6 is a left elevation view of the claimed design of FIG. 1;

FIG. 7 is a top plan view of the claimed design of FIG. 1; and,

FIG. 8 is a bottom plan view of the claimed design of FIG. 1. The ornamental design which is claimed is shown in solid lines in the drawings. Broken lines formed of unequal length dashes (i.e., dash-dot) represent bounds of claimed portions of the design. Broken lines formed by equal length dashes (i.e., dash-dash) illustrate unclaimed portions of the design. The broken lines in the drawings are for illustrative purposes only and form no part of the claimed design.
